UNITED STATES PATENT OFFICE.

JAMES H. WEBBER, OF CARROLLTOWN, PENNSYLVANIA.

CHAIN HOOK.

Application filed August 17, 1925. Serial No. 50,781.

This invention relates to improvements in hooks for use upon motor vehicle skid chains and the like and which contemplates the provision of a plate having a notched end portion for receiving the loops of a side chain and having a correspondingly shaped latch plate hinged to its outer end and when folded thereupon will provide pockets between the notched portions for completely housing the loops of the side chains wherein its accidental displacement therebetween is prevented.

Another object of my invention is the provision of a spring upon the plate and adapted to receive therein the inner end of the latch plate for rigidly holding the entire hook in a locked position for eliminating the displacement of a side chain link therein.

With the above and other objects in view, the invention further includes the following novel features and details of construction, to be hereinafter more fully described, illustrated in the accompanying drawing and pointed out in the appended claim.

In the drawing:—

Figure 1 is a fragmentary side elevation of my invention shown in a locked position.

Figure 2 is a side elevation showing the latch plate open.

Figure 3 is a vertical sectional view taken on line 3—3 of Figure 1.

Referring to the drawing in detail, wherein like characters of reference denote corresponding parts, the reference character 10 indicates a relatively flat plate forming an abutment or shoulder 11 adjacent its forward end from which extends a locking plate 12 having a plurality of reversely extending notched portions 13 therein, the purpose of which will be presently apparent. Pivoted as at 14 to the rear end portion of the plate 10 is an end link 15 of a chain, not shown, while washers 16 and 17, arranged upon the rear and forward end portions of the plate 10, include elongated slots 18 therein for facilitating their sliding movement upon the said plate 10 and eliminating any rotation thereon. Encircling the plate 10 and having its respective end portion engaging the corresponding inner side of the washers 16 and 17 respectively and holding the washer 17 against the abutment or shoulder 11 is a compression spring 19, the purpose of which will be presently apparent. In order to provide means for rigidly holding the opposing end link 20 of the chain mentioned, within the re-

versely disposed notched portions 13 of the locking plate 12, I provide a latch plate 21 having its forward end pivoted as at 22 to the corresponding end portion of the locking plate 12 and which further includes a plurality of reversely disposed notched portions 23 upon its under side for registration with the notched portions 13 in the locking plate 12 when swung into the positions as clearly illustrated in Figure 1 of the drawings. The outer free end of the latch plate 21 includes an abutment or shoulder 24 adjacent its outer end while its remaining links terminating in a reduced extension 25 which when in a locked position lies flush with the outer side of the plate 10 within the inclosure defined by the compression spring 19 and extending through the elongated slotted portion 18 in the washer 17 whereby the reversely disposed notched portions 13 and 23 are brought into registration and forming such inclosures for the end link 20 of the chain, not shown, as will not permit any accidental displacement of the same therein.

In the mode of operation of the present invention it is clearly apparent and manifest that the end link 20 may be arranged in any one of a plurality of their reversely disposed notched portions 23 in the latch plate 21 and when swung rearwardly therewith into the position as clearly illustrated in Figure 1 of the drawing, it will be noted that the said inner looped end of the link 20 will be completely inclosed between the reversely disposed notched portions 23 in the latch plate 21 and notches 13 in the locking plate 12 after which the washer 17 is moved rearwardly upon the plate 10 against the tension of the compression spring 19 in allowing ample and sufficient room for the reduced extension 25 of the latch plate 21 to swing rearwardly and lie flush against one side of the plate 10 after which the washer 17 is released and the reduced extension 25 received within the elongated slot 18 in the washer 17 and held rigidly in a locked position.

The invention is susceptible of various changes in its form, proportions and minor details of construction, and the right is herein reserved to make such changes as properly fall within the scope of the appended claim.

Having thus described my invention what is claimed is:

A chain hook for use upon side chains comprising a relatively flat plate having a

chain end pivoted to one end thereof, an enlarged locking plate provided upon the forward end of the flat plate and including reversely disposed notched portions upon its upper side, a correspondingly shaped latch plate pivoted to the forward end of the locking plate, a reduced extension on the inner free end of the latch plate, a pair of washers including elongated slots centrally thereof arranged upon the flat plate and receiving

the reduced extension of the latching plate, and a compression spring encircling the flat plate, and having its opposite end portion engaging in the corresponding inner sides of the washer for rigidly holding the reduced extension of the latch plate in a locked position upon the flat plate. ¹⁵

In testimony whereof I affix my signature.

JAMES H. WEBBER.
